ATTORNEYS.

UNITED STATES PATENT OFFICE.

JOHN F. CARROLL, OF BUFFALO, NEW YORK.

DESIGN FOR A FLOWER-POT OR ANALOGOUS ARTICLE.

52,559.

Specification for Design.

Patented Oct. 15, 1918.

Application filed June 24, 1918. Serial No. 241,715. Term of patent 3½ years.

To all whom it may concern:

Be it known that I, JOHN F. CARROLL, citizen of the United States, residing at Buffalo, in the county of Erie and State of New York, have invented a new, original, and ornamental Design for a Flower-Pot or Analogous Article, of which the following is a specification.

The figure in the drawing is a perspective view of a flower pot, showing my new design.

I claim—

The ornamental design for a flower pot or analogous article, substantially as shown.

JOHN F. CARROLL.

Witnesses:

C. W. PARKER,

A. L. McGEE.
